S. I. FLOURNOY

METER BOX

Filed Feb. 13, 1922

INVENTOR
Samuel I. Flournoy
BY Arthur C. Remm.
ATTORNEY

UNITED STATES PATENT OFFICE.

SAMUEL I. FLOURNOY, OF KANSAS CITY, MISSOURI, ASSIGNOR TO WALTER S. DICKEY,
OF KANSAS CITY, MISSOURI.

METER BOX.

Application filed February 13, 1922. Serial No. 536,285.

To all whom it may concern:

Be it known that I, SAMUEL I. FLOURNOY, a citizen of the United States, residing at Kansas City, in the county of Jackson and

5 State of Missouri, have invented certain new and useful Improvements in Meter Boxes; and I do declare the following to be a full, clear, and exact description of the invention, such as will enable others 10 skilled in the art to which it appertains to make and use the same, reference being had to the accompanying drawings, and to the figures of reference marked thereon, which form a part of this specification.

15 This invention relates to a novel form of meter box particularly designed to be embedded or sunk into the ground to constitute a box or housing for the protection of fluid meters and the invention is particularly applicable for use in connection with 20 water meters.

Water meters are usually maintained outside the premises or buildings so that they will be available for inspection at all times 25 and they are usually contained in a casing commonly known as a meter box. The lid or cover for the casing is usually flush with the ground and in view of the fact that it is readily accessible, it sometimes happens 30 that an unauthorized person removes the cover to tamper with the meter, or as sometimes happens, the meter box cover is removed, allowing dirt and rubbish to enter the meter box or permitting it to fill up 35 with water and surface drains with the obvious disadvantages.

It is the primary purpose of my invention to provide an improved meter box cover which may be normally fastened to the meter box with an appropriate locking 40 means controllable only by a special key to be in the possession of authorized persons only, so that the lock cannot be moved to unlocking position with the ordinary tools or with an ordinary key, socket wrench or 45 the like.

The peculiarly novel features of the invention will be apparent by reference to the following description in connection with the accompanying drawings, in which—

50 Fig. 1 is a vertical, longitudinal, sectional view through a meter box, showing the meter therein, the removable lid being shown in edge elevation.

Fig. 2 is a bottom plan view of the meter box cover ring and the lid associated therewith, the lock being shown in locked position.

Fig. 3 is an enlarged fragmentary, longitudinal, sectional view through the lid, showing the locking mechanism in edge elevation.

Fig. 4 is a fragmentary, perspective view of the key and the locking elements, removed, and

Fig. 5 is a fragmentary perspective view 65 of the cover ring and the lid.

1 designates the service pipe which may be connected to the main in the usual manner and in the line is a meter 2, to be protected by the box. The box is shown as 70 comprising a cylinder 3 having openings 4 and 5, through which the two branches of the main may pass in the usual way.

Located upon the upper edge of the cylinder 3 is a cover ring or collar 6, substantially conical and having a peripheral flange 7 with lugs 8, which may bear against the inner face of the cylinder 3 so that the ring or collar will be properly centered with respect to the cylinder 3.

The upper end of the collar or ring 6 receives the cover plate 9, which is preferably slightly greater in diameter than the upper end 10 of the ring so that it will act as a water shed.

The cover plate 9 is provided with locating projections or lugs 11, which are adapted to engage corresponding notches 12 in the upper edge of the ring, the lugs 11 and notches 12 being crosswise of the wall 90 of the ring so that when the lugs 11 engage the notches 12, the cover plate 9 cannot be turned about its axis. This is important because the inter-engaging of the lugs with the notches prevents liability of the lock being worked loose.

The cover plate 9 is provided with a countersunk portion or recess 13 in its top face and a recess 14 in its bottom face. Adjacent to the recesses are depending 100 bracket lugs 15 and 16, which are provided with slots 17 and 18, which receive a lug-supporting bar 19, as will be clearly seen in Fig. 3.

Resting upon the bar 19 is a latching 105 lever having a tongue portion 20 and a finger 21 at substantially right angles there-

to. At the angle of the latching bar is a pivot projection 22, which engages the opening 14 so that it will be held in position to turn about its axis but will be prevented from taking any other position.

The projection 22 is held in engagement with a recess 14 by the close clearances between the bottom face of the cover 9 and the bar 19.

10 The bar 19 also supports a latch-bar-actuating finger 23, which has a shaft 24 extending through an opening 25 in the bottom of the recess 13. The upper end of the shaft is provided with a polygonal portion 26, preferably triangular in cross section, to receive the triangular socket 27 of the key 28. I prefer to construct the portion 26 triangular as it apparently resists the application of wrenches, pliers and conventional 20 keys and because it will require a special socket key to turn it.

The free end of the finger 23 is provided with a notch-engaging projection 29, to engage the serrated portion 30 on the latch bar 20. The free end of the latch bar for engagement with the under side of the edge 10 of the collar 6 is slightly chamfered, as at 31.

30 The latch members 20 and 23 can be applied to the cover plate 9 by introducing the projection 22 into the socket 14 and the shaft 24 through the opening 25, as shown in Fig. 3, and then sliding the bar 19 through the openings 17 and 18 in the lugs 15 and 16, when the lock or latch will be assembled.

35 The collar 6 will be centered with respect to the cylinder 3 by the lugs 8. Then dirt or concrete will be tamped about it so that it will have the position shown in Fig. 1. 40 The cover plate will then be placed on the upper edge 10 of the collar 6 and turned until the lugs 11 drop into the notches 12, whereupon the cover plate 9 will be held against further rotative movement with respect to the collar. The operator will then 45 apply the key, turning it so that the finger 23 will ride over the serrated edge of the lock lever 20 to cause the portion 31 to engage under the edge 10 of the collar 6, the projection 29 being maintained in engagement with the serrated edge so that it will not ordinarily be moved out of engagement therewith by vibrating the lid. The lid will then be securely fastened to the collar so

that it cannot be taken off unless a special 55 key is used.

When the key is caused to engage the end 26 of the shaft 24 and turned in a direction to swing the engaging end of the finger 23 out of engagement with the serrated portion 60 30, the edge of the finger 23 will strike against the inner edge of the hooked-shaped arm or projection 21 so as to swing the lock member 20 out of engagement with the inner wall of the cone-shaped ring or collar 6. 65 Then the lid can be taken off.

70 It will be observed that the device is inexpensive to manufacture, simple in construction and adapted to efficiently hold the cover or lid in place so that it cannot be removed by unauthorized persons and thereby it affords an efficient protection for the meter 2.

75 What I claim and desire to secure by Letters-Patent is:

1. A meter box cover comprising a disk having depending members on its under side provided with transverse slots, a bar in the slots, the cover having a recess facing the bar and an opening spaced from the recess but also facing the bar, a pivoted lever having a trunnion fitting into the recess and having a meter box engaging end, a projection at right angles to the lever, and a swing 85 finger having a trunnion projecting through the opening in the cover and provided with a key-engaging portion, the finger being movable in one direction to cause the locking lever to move into functional 90 position and movable in another direction to cause the lever to move in a non-functional position, the finger and lever being held in co-operative positions by the bar.

2. A meter box cover having depending 95 projections provided with transverse slots, a removable bar in said slots, a locking lever resting on the bar and having a trunnion projecting into a recess in the cover, and an actuating finger for the locking lever resting on the bar and having a trunnion projecting through the cover with a key-engaging end whereby when the finger is moved in one direction, it will move the lever into functional position and when moved in an opposite direction, it will move the lever out of functional position.

In testimony whereof I affix my signature.
SAMUEL I. FLOURNOY.
